HOPPER NOZZLE

Henry H. Logan, Chicago, Ill., assignor to Logan Engineering Co., Chicago, Ill., a corporation of Illinois

Application December 7, 1939, Serial No. 308,015

10 Claims.

(Cl. 222—1)

My invention relates to hopper nozzles, that is, compressed fluid nozzles to be placed in the hopper bottoms of bins, railway cars, and the like, to promote flow and especially to relieve the jamming or stoppage occasioned by arching.

One object of my invention is to produce a more effective action for a given size of nozzle and a given supply of compressed air therefor. This objective I attain by an arrangement and placement of the nozzle which better utilizes not only the direction given the emerging air stream, but also the expansive forces of the emerging air stream.

Another object of my invention is a nozzle which may be placed flatwise upon the inner surface of the hopper, as distinguished from being recessed thereinto, and which still does not substantially impede the flow of the material nor catch the material. Such a superficially applied nozzle is more convenient of application to both new and existing hoppers.

Another and related object is a nozzle in the form of a single unit which, aside from its anchoring bolts or screws and its feed pipe, is a single piece and which, being a separate unit in itself, can be applied along with like nozzles in whatever number and arrangement the particular circumstances require. This affords a greater flexibility and universality of application than with hopper nozzles which are preformed in fixed gangs. With my nozzles, it is a relatively simple matter to add additional nozzles or to change the locations of nozzles already installed. This facilitates the determination, by actual experiment under working conditions in any given hopper, of the optimum placement and arrangement of the nozzles, together with a minimum number of nozzles.

A further object is the improved provision for a quick momentary gang operation of the nozzles for breaking any stoppage or jamming due to arching or the like. An auxiliary object in this connection is a provision for such a momentary gang operation of the nozzles, wherein a relatively large quantity of compressed air is used in a short time, but still permitting the economical use of a small size feed pipe line from a distant source of compressed air. This is important because the compressor and storage tank for the compressed air supply in an industrial plant are frequently located a great distance from the hoppers.

Quick acting and efficient hopper nozzles are much to be desired in industrial plants. A stoppage of material in the hopper represents a loss

of time until the stoppage is relieved. The practice of pounding on hopper walls shortens the life of the hopper. Reaching up from beneath with a pole is dangerous because of the likelihood of a sudden avalanche of material when the arching is successfully broken, before the workman can get away. The practice of working with a pole from the top of the bin is also dangerous because of choking from the dust and the danger of being smothered, should the workman accidentally drop to the bottom of the hopper. In either case, the bin or the bottom of the discharge passage has to be opened up for manual access and this often releases objectionable dusts which normally are confined by covers for the bin and enclosed canvas or rigid conduits leading from the discharge end of the hopper. With my hopper nozzles the nozzles are actuated and the stoppage relieved without the necessity of opening up any doors or passageways through which objectionable dust might be exhausted.

The foregoing, together with further objects, features and advantages of my invention, are set forth in the following description of a specific embodiment thereof and illustrated in the accompanying drawing, wherein:

Fig. 1 is a conventionalized vertical cross-section of a bin with a battery of my nozzles installed in its hopper bottom, together with a somewhat diagrammatical layout of the air supply system thereto;

Fig. 2 is a front face elevation of one of the nozzles, which may be considered as taken on the line 2—2 of Fig. 3;

Fig. 3 is a vertical transverse cross-section, taken on the line 3—3 of Fig. 2 or Fig. 1;

Fig. 4 is a section of the nozzle taken on the line 4—4 of Fig. 3, in a plane parallel with the wall of the hopper;

Fig. 5 is a top view of the nozzle;

Fig. 6 is a bottom view of the nozzle, and

Fig. 7 is an intermediate horizontal section, taken on the line 7—7 of Fig. 4.

In Fig. 1 I have shown a four-sided bin 10 with a hopper 11 at the bottom having a corresponding set of four inwardly inclined walls. This bin may contain ground feed, flour, sugar, cement, or like material. On the inside face of each of the hopper walls I have shown mounted a set of my nozzles 12. The number and arrangement of the nozzles will depend upon the size, slope and other characteristics of the hopper and also to a certain extent on the nature of the material being handled and the pressure of the air supply available. Especially for the larger sizes of

hoppers it is usually desirable to arrange the nozzles on each hopper wall in a quincunx pattern, that is, a staggered arrangement in parallel horizontal rows with the nozzles in even number rows offset from those in odd number rows. Each nozzle 12 is fed by a pipe stem 13 extending through the wall of the hopper and the pipe stems 13 are connected without the wall to manifolds 14 branching from a delivery pipe 15 leading from a compressed air receiver 16.

Each nozzle 12 is flat on its back side and its back side is placed against the flat inside face of the hopper wall 11 as shown in Fig. 3. The nozzle is preferably a one-piece casting streamlined and buffed on its exposed surface to present a minimum resistance to the flow of material thereover. It is attached to the hopper wall by a pair of fastening elements 17, one at the top and one at the bottom, extending through suitably located holes. The fastening elements are preferably of a headed variety such as wood screws, expansion bolts, or bolts and nuts, depending largely on whether the material of the hopper wall be wood, concrete, sheet metal, or cast iron. In order to avoid obstruction to free sliding thereby of the material within the hopper, the heads of the fastening elements are countersunk into the outer face of the nozzle body within counterbores recessed in such face at the holes for the elements. A hole is drilled through the hopper wall for passage of the feed stem 12, as shown in Fig. 3.

The nozzle is preferably segment-shaped, with its apex pointing upwardly. The nozzle has a flat hollow interior 18 formed by a flat back plate 19 and a slightly rounded or arched face plate 20. The face plate 20 is joined to the back plate 19 at the apex and along the diverging lateral margins, but at the bottom is not connected, leaving a narrow discharge opening 21, as best seen in Fig. 6. The lower screw or bolt 17 passes through an ear 22 at the bottom of the back plate.

The back plate 19 is provided with a boss 23 tapped to receive the end of the feed pipe stem 13 and of sufficient thickness to provide adequate anchorage for a threaded end of the pipe stem. The face plate 20 in the longitudinal cross-section of Fig. 3 is curved or bulged outwardly, with the greatest bulge opposite the feed stem 13. This affords substantial air passage for air issuing from the stem 13, despite the additional thickness of the boss 23 at this region.

At the lower end of the nozzle the face plate 20 is spaced only a short distance from the back plate 19, whereby the long narrow discharge slot or opening 21 is formed. To lighten the casting and facilitate coring of the hollow interior 18, a generous opening 24 may be left in the back plate 19, as best shown in Fig. 4. As will be seen from the several cross-sections and as indicated by the surface shading in Figs. 2 and 5, the exposed exterior of the nozzle and especially those portions of the exposed surface which in whole or in part face upwardly, are carefully streamlined with a view to reducing the resistance to flow of material over the nozzle, and no abrupt up-facing shoulders are left which might catch the material or impede its flow. In general, the nozzle is very flat and thin to reduce resistance to flow of material.

Compressed air entering the nozzle through the feed stem 13 passes downwardly through the hollow interior passage 18 which, as best shown in Fig. 4, diverges downwardly in a fan shape.

5 The discharge opening 21, as shown in Fig. 3, is defined by substantially parallel and closely spaced surfaces extending some distance back or inwardly from the discharge end. This serves to discharge the air in a thin sheet substantially parallel with the hopper wall, but in a diverging fan shape. Thus, if the nozzles are not placed too far apart laterally, the fan-shaped flat streams of air emerging from the nozzles will 10 combine into a continuous flat sheet of air a short distance below the nozzles.

When a stoppage in the flow of material in the hopper has been caused by the arching of the material, it is not always sufficient to clear a central passage through the arch. For example, it is well known that an annular arch or dome may be self-supporting even though its central portion is removed. To put it another way, a truncated conical wall, although open at the top, may be sufficiently self-arched to resist collapse from its own weight. It is for this reason that I do not place my nozzles in the center of the hopper, but, instead, along the sides. But even nozzles placed at the sides of the hopper are not always effective if they merely direct jets of air horizontally to the center of the hopper. They may merely form round or cylindrical holes for the jets without entirely breaking the arching. This is in much the same manner that circular windows can easily be formed in a truncated arched dome, even though open at its top, without causing its collapse.

30 The reason that my nozzles are so peculiarly effective is that they discharge the compressed air as flat and relatively wide jets parallel with and close to the walls of the hopper. Thus, they 35 attack the arch of material at its most vulnerable point—its base or abutment. But the air jets from my nozzles do more than take material away from the base or abutment of the arch, which could merely let it drop down farther toward the bottom opening of the hopper.

40 The air in the flat jets is compressed air of, say, 90 pounds per square inch when it enters the nozzle. As it emerges from the nozzle its 45 pressure decreases somewhat due in part to the divergence of the jet. But still the air in the jet is relatively highly compressed and, being compressed, it presses in all directions including, most importantly, an inward expansion; that is, an expansion away from the adjacent fixed wall of the hopper. Compressed air entering the nozzle at 90 pounds pressure per square inch will, after it has emerged into the fan-shaped thin jet, even 50 some distance below the nozzle, exert hundreds of pounds of inward pressure against each square foot of the base or abutment of the arch, forcing the material into the center where it quickly collapses.

55 In this way my nozzles achieve unusually effective and quick collapsing of the arching of the material by three combined actions: First, the air jets carry or eat away the material at the base of the arch where it abuts the sides of the hopper. Second, the compressed air is inserted as a laterally expanding flat sheet of compressed air between the sides of the hopper and the arched material, with the result that the arched material is pushed in toward the center under tremendous pressure which it cannot resist. Third, the general direction of the air jets being downward, the material of the collapsed arch is rapidly urged downwardly in the hopper to its bottom outlet, so that the arched material 60 is carried out of the hopper as part of an almost

instantaneous actuation of the nozzles. Otherwise, in a very brief or momentary actuation of the nozzles, although the nozzles might collapse the arch, the material of the collapsed arch might reform itself into an arch after the actuation of the nozzles was terminated and before that part of the material which had caused the arching had been discharged from the hopper. This latter point is of especial importance in those instances where the arching has been caused by an unusual moisture content in a certain portion or stratum of the material in the bin or where the material is of a character which, once having been compressed under the head pressure on an arch, is more apt to re-arch.

The film of compressed air introduced along the hopper wall and between it and the mass of material serves as what might be termed a pneumatic lubricant to facilitate a relatively frictionless flow of material down the wall.

My nozzle, in its preferred embodiment, is thus characterized by its external flatwise application to the inside surface of the hopper wall; its streamlined flatness; the minimum resistance it affords to downward passage of material; the flatness of the emitted air jet and its parallelism with the wall; the downward divergence of the flat air jet; the inward expansive force of the compressed air of the flat jet forcing the material inwardly toward the center of the hopper; the general downward impetus given the material by the jet; the separateness of the individual jets with the attendant flexibility of their placement in relation to other jets; and the superficial application of the nozzles to the hoppers.

Referring again to Fig. 1, the supply pipe 15 from the compressed air receiver 16 to the nozzle manifolds 14 is supplied with a solenoid valve 25. The circuit of the solenoid is fed from a power line and controlled by a push button switch 26 conveniently located on or near the hopper. When the attendant first detects a slowing up or stoppage of feed from the hopper, all he need do is press the push button switch 26. This causes the solenoid valve 25 to open and a charge of compressed air from the receiver 16 will flow through the nozzles to relieve stoppage.

The solenoid valve 25 may have a timing feature such as a dashpot, or the switch 26 may be a timing switch. However, I find it practicable to dispense with any timing features in the valve or its control and instead to use the limited amount of air in the receiver 16 automatically to terminate the nozzle action even if the switch 26 be left closed too long.

In this connection I call attention to another advantage in the use of the receiver 16 which is preferably located not far from the hopper. The receiver 16 is fed by a long feed pipe 27 from a main compressed air supply tank 28 charged by a compressor 29. In the usual plant installation the hopper may be hundreds or thousands of feet away from the main supply tank 28. In that case the feed line 27 running to the receiver 16 may be of very small diameter and therefore economical. This is possible because the nozzles are actuated only infrequently and the feed pipe 27, although very small, has on the average a long interval during which it may recharge the receiver 16. On the other hand, the supply pipe 15 leading from the receiver 16 to the manifolds 14 may be an amply large pipe and, being relatively short, it does not involve much piping expense. If the local reser-

voir 16 was not employed it would be necessary to run a large pipe such as 15 all of the long distance from the hopper to the main supply tank 28.

5. While I have described and illustrated this specific embodiment of my invention, I contemplate that many changes and substitutions may be made without departing from the scope and spirit thereof.
10. I claim:
1. A hopper nozzle for superficial application to the inside surface of a hopper wall, comprising a thin flat segment-shaped body having a flat back to lie against the hopper wall, a front 15 streamlined downwardly from the apex of the segment to minimize resistance to downward flow of material along the surface of the wall, a flat segment-shaped hollow interior, a thin mouth for the hollow interior extending across the bottom
  20. at the lower edges of the front and back to discharge a thin fan-shaped jet of air downwardly along the surface of the wall, and a passage through the back for bringing compressed air into the hollow interior.
  25. 2. In a hopper having a sloping wall for the discharge of granular or powdery material, a multiplicity of nozzles according to claim 1 separately mounted superficially upon the inner surface of the wall and arranged in quincunx 30. pattern over a field of the wall with horizontally spaced adjacent nozzles within the fan-shaped jet emitted by a nozzle intermediate but first above the said spaced nozzles, whereby substantially all the area of the wall within said field is covered by the emitted jets.
  35. 3. A hopper nozzle for superficial application to the inside surface of a hopper wall, comprising a thin flat segment-shaped body having a flat back wall to lie against the hopper wall, a front wall streamlined downwardly from the apex of the segment to minimize resistance to downward flow of material along the surface of the wall, the front and back walls being joined along their tops and their lateral margins to leave a flat segment-shaped hollow interior between the front and back walls, a thin mouth for the hollow interior extending across the bottom between the lower edges of the front and back walls to discharge a thin fan-shaped jet of air downwardly along the surface of the wall, and a tapped hole through the back wall near the upper end of, and opening into, the hollow interior for receiving the threaded end of a compressed air feed pipe extending through the hopper wall.
  40. 4. A hopper nozzle, according to claim 3, wherein a hole passes through the body, adjacent its apex and above the tapped hole and hollow interior, for the passage of a headed threaded member for anchoring the body to the wall, the hole having a head-receiving counter bore recessed into the outer face of the body.
  45. 5. A hopper nozzle, according to claim 3, wherein a hole passes through the body, adjacent its apex and above the tapped hole and hollow interior, the back wall has a lip extending below the front wall, and a hole passes through the lip, the holes being adapted for passage of headed threaded members for anchoring the body to the wall and being countersunk to receive the heads of the threaded members.
  50. 6. In combination with the downwardly sloping inner surface of a hopper adapted for containing and directing compactible discrete ma-

terial downwardly toward an outlet in the hopper, pneumatic flow accelerating means including a pressure fluid nozzle having a generally flattened body open on one face and enclosed on its opposite face by a thin arched outer wall, and means for connecting said body superficially on the hopper surface in such relation that the underlying portion of the hopper surface closes said open face and cooperates with said nozzle wall to form a chamber for receiving pressure fluid, the lower edge of said body having a narrow slot-like discharge mouth for directing downwardly along said hopper surface a generally flat jet of the pressure fluid.

7. In combination with the sloping wall of a hopper, a pneumatic flow accelerator comprising a set of separate spaced nozzles disposed in a uniform staggered pattern and adapted to be fed with compressed air, each nozzle having a narrow slot-like port opening close to and parallel with the wall to discharge a thin fan-like sheet of compressed air downwardly parallel to the surface of the wall between the wall and material that may be on the wall, the relative spacing of the nozzles being such that the nozzles lower down on the wall are within the side sweep of the nozzles higher up on the wall so that the respective sheets of compressed air from all of the nozzles in the set combine to form a film of air over the surface of the wall to pneumatically separate and force the entire body of material inwardly away from the wall by expansion of the air in the film.

8. The method of relieving arching stoppage of material in a hopper which consists in, from

time to time when the material arches, distributing a hopper-lining flat film of compressed air along substantially the entire arch-biasing area of a wall of the hopper and between said area and the wall-opposing surface of the mass of material in the hopper to the substantial exclusion of an inwardly directed mass-tunneling stream of air, and inwardly lifting the material by the expansion of the film of compressed air reacting against the hopper wall, without substantial pneumatic agitation of the material.

9. The method of dissipating the arching of material in a hopper which consists in pneumatically lubricating an arch-basing wall of the hopper by downwardly injecting a film of compressed air along the wall and over the arch-basing field thereof, and inwardly lifting the adjoining material by the expansion of the film of compressed air between the wall and the wall-opposing surface of the mass of material in the hopper.

10. The method of relieving arching stoppage of material in a hopper which consists in, from time to time when the material arches, downwardly distributing a hopper-lining film of compressed air between the arch-basing area of a wall of the hopper and the hopper-opposing surface of the mass of material therein, to the substantial exclusion of an inwardly directed mass-tunneling stream of air and of substantial centrifugal agitation of the mass, and inwardly lifting the material by the expansion of the film of compressed air reacting against the hopper wall.
